ENGINE STARTER GEARING

Burr W. Jones, Elmira Heights, N. Y., assignor to
 Bendix Aviation Corporation, South Bend, Ind.,
 a corporation of Delaware

Application April 30, 1940, Serial No. 332,531

11 Claims. (Cl. 74—6)

The present invention relates to engine starter gearing and more particularly to a device for manually controlling the connection of a starting motor with a member of an engine to be started.

Manually controlled starter gearing commonly comprises a pinion rotatable from a starting motor and movable axially into and out of mesh with an engine gear by shifting means which may be operated by manually or magnetically actuated linkages. In starters of this type, some form of overrunning connection between the pinion and starting motor is usually provided to prevent the starting motor from being rotated at excessive speed when the engine starts, prior to withdrawal of the pinion from the engine gear. In some devices of this character, instead of utilizing an overrunning clutch, certain forms of speed-controlled devices have been used to withdraw the pinion upon rotation thereof at excessive speeds. These devices, however, have the disadvantage that demeshing of the pinion may occur before a true start of the engine is secured, and it then becomes necessary to re-engage the pinion with the engine gear in order to resume cranking. If the operator permits this action to take place automatically by maintaining the linkage in operative position, severe milling of the pinion teeth against the teeth of the engine gear may take place.

It is an object of the present invention to provide a novel manual shift for starter gears in which the starting pinion is moved manually into driving position but may be returned to idle position by automatic means dependent on the speed of rotation of the starting motor.

It is another object to provide such a device in which the manual shifting means includes spring members adapted to yield in case of tooth abutment of the pinion and engine gear, and thereafter snap the pinion into mesh with an engine gear.

It is another object to provide such a device in which the spring members are arranged to be deflected by centrifugal force so as to withdraw the pinion from mesh when the starting motor has attained a predetermined speed of rotation.

It is another object to provide such a device in which an overrunning clutch is interposed between the centrifugal controlling device and the pinion whereby the centrifugal device is independent of the speed of rotation of the pinion.

It is another object to provide such a device in which the overrunning clutch is controlled by the shifting means so as to be closed by the

meshing action of the shifting means and opened by the demeshing action thereof.

It is a further object to provide such a device in which the shifting means is arranged to be re-enforced after initial mesh of the pinion is secured so as to afford a substantially positive control of the pinion and overrunning clutch.

Further objects and advantages will be apparent from the following description taken in connection with the accompanying drawings in which:

Fig. 1 is a side elevation partly in section of starter gearing embodying a preferred form of the invention, the parts being shown in idle position;

Fig. 2 is a similar view showing the parts in cranking position;

Fig. 3 is a similar view showing the parts in the positions assumed after the engine starts but before the shifting mechanism is returned to idle position;

Fig. 4 is a similar view showing the parts in the positions assumed during the meshing operation when a tooth of the pinion abuts against a tooth of the engine gear;

Fig. 5 is a detail in perspective and partly in section of the members of the overrunning clutch shown in disassembled relation;

Fig. 6 is a detail in perspective of the shift collar;

Fig. 7 is a section taken substantially on the line 7—7 of Fig. 1; and

Fig. 8 is an end view from the right of the drive illustrated in Fig. 1.

In Fig. 1 of the drawings there is illustrated a power shaft 1 which may be the extended armature shaft of a starting motor, not illustrated. A sleeve 2 is fixedly mounted thereon as by means of a "double-D" section 3 formed on the end of the power shaft and a bore 4 conforming thereto in the end of the sleeve, a split lock ring 5 seated in a groove on the end of the power shaft being provided to maintain the sleeve against longitudinal movement.

A driving clutch member 6 is splined on the sleeve 2 as by means of inwardly extending lugs 7 which slidably engage in slots 8 of the sleeve. A shift collar 9 is slidably journaled on the sleeve 2, normally resting against a shoulder 11 formed on the end of said sleeve. Means for imparting longitudinal movement from the shift collar to the driving clutch member 6 is provided in the form of a plurality of flat spring members 12 pivoted at their ends as indicated at 13 and 14 to the shift collar and driving clutch member

respectively in such manner as to form in effect a yielding toggle connection therebetween. Weight members 15 are mounted rigidly on the springs 12 intermediate their ends at points corresponding to the hinges of the toggles formed by the springs. Weights 15 bow out the springs by resting on the surface of sleeve 2 when the parts are in idle position as shown in Fig. 1, and further bow out the springs 12 to withdraw the pinion from mesh under the action of centrifugal force when the shift collar and clutch member are rotating above a predetermined minimum speed. The natural set of the springs 12 is inward toward the axis of the drive so that the weight members 15 are ordinarily pressed inward with sufficient force to resist the action of centrifugal force at speeds below the predetermined minimum.

A pinion 16 is slidably journalled on the power shaft 1 for axial movement into and out of engagement with a member such as a gear 17 of an engine to be started. A barrel member 18 is rigidly connected to the end of the pinion in any suitable manner, and a driven clutch member 19 is fixed in the barrel as by means of radial lugs 21 engaging in slots 22 of the barrel. Clutch members 6 and 19 are provided with teeth 23 and 24 respectively which are adapted to engage and transmit rotation from the driving clutch member 6 to the driven clutch member 19, but which are beveled off as best seen in Fig. 5 in such a manner as to disengage when the driven clutch member overruns the driving clutch member. A spring 25 is interposed between the clutch members in order to normally maintain them out of engagement.

Driving clutch member 6 is maintained in the end of the barrel 18 by suitable means such as a split lock ring 26. Means for defining the operative position of the pinion and its associated parts is provided in the form of a stop ring 27 seated on the inner end of the sleeve 2 against a lock ring 28.

Slots 8 of the sleeve 2 are terminated by inclined shoulders 29 which are normally located a short distance away from and in axial alignment with the positions assumed by the weight members 15 when the parts are in their idle positions. Weight members 15 are formed to enter slots 8 by impulsion of the inward set of springs 12 when the weights are brought into registry with the slots by longitudinal movement of the shift collar 9 to the left. When the weight members thus enter the slots 8, the springs 12 flex inwardly past their straight or dead-center positions to the positions illustrated in Fig. 2. When so flexed, the springs are re-enforced or stiffened by the bearing of the weight members against the power shaft 1 inasmuch as longitudinal compression of the springs 12 then tends to bend the springs inwardly rather than outwardly as is the case when the parts are in idle position. The springs 12 thus become substantially rigid in their transmission of longitudinal motion from the shift collar to the driving clutch member 6 for closing the clutch after the weights 15 enter the slots 8.

In operation, starting with the parts in the positions illustrated in Fig. 1, motion of the shift collar 9 to the left by any form of manually or magnetically operated linkage, not illustrated, is transmitted yieldingly by the springs 12 to the driving clutch member 6 since at this time the springs are bowed outwardly and longitudinal pressure tends to increase the outward flexure 75

thereof. The longitudinal motion of the driving clutch member 6 is transmitted through the spring 25 to the driven clutch member 19 and from thence through the barrel 18 to the pinion 16 to move it into engagement with the gear 17. If the teeth of the pinion 16 enter properly in the tooth spaces of the gear 17, this longitudinal motion continues until the driven clutch member 19 engages the stop ring 27, at which time the pinion is fully meshed with the engine gear. As soon as the parts have been shifted sufficiently to permit the weight members 15 to ride down the inclines 29 of the sleeve 2 and bear against the power shaft 1, the springs 12 become re-enforced by the bracing action of the weight members against the power shaft so that when the driven clutch member 19 engages the stop 27, further pressure of the shift collar 9 causes the spring 25 to yield and the teeth 23 of the driving clutch member 6 to engage with the teeth 24 of the driven clutch member 19.

The starting motor being now energized in any suitable manner, rotation of the power shaft 1 thereby is transmitted from the sleeve 2 through clutch members 6 and 19 and barrel 18 to the pinion 16 to crank the engine. When the engine starts, the driven clutch member 19 overruns the driving clutch member 6 so that the acceleration of the pinion 16 by the engine gear is not transmitted back to the starting motor. If the operator releases the shifting mechanism, the parts are returned to idle position by the usual return spring of the linkage. If, however, the operator does not so release the shifting mechanism and thereby open the switch of the starting motor, the motor will rotate at high speed, thus rotating the shifting mechanism whereby the weights 15 move out as shown in Fig. 3, withdrawing the pinion and its associated parts back to their idle positions although the shift collar 9 is maintained in operative position. When the operator thereafter releases the linkage, the shift collar returns to its idle position as shown in Fig. 1.

If, during the meshing operation, a tooth of the pinion should abut against a tooth of the engine gear as shown in Fig. 4, the spring members 12 bow outwardly as there shown, thus permitting the shift collar to move sufficiently to allow the starting switch to be closed. As soon as initial rotation of the power shaft by the starting motor takes place, the teeth of the pinion are indexed into proper registry with the tooth spaces of the engine gear and the springs 12 contract and snap the pinion into mesh with the engine gear, whereupon meshing and cranking take place as usual.

Although but one embodiment of the invention has been shown and described in detail, it will be understood that other embodiments are possible and various changes may be made in the design and arrangement of the parts without departing from the spirit of the invention as defined in the claims appended hereto.

What is claimed is:

1. Engine starter gearing including a power shaft, a pinion slidably journalled thereon, a sleeve fixed on the shaft, a driven clutch member non-rotatably connected to the pinion, a driving clutch member slidably mounted on the sleeve and connected to rotate therewith, a shift collar slidably mounted on the sleeve, yielding means connecting the shift collar to the driving clutch, and means responsive to rotation of the power

shaft above a predetermined speed for contracting said yielding means.

2. Engine starter gearing including a power shaft, a pinion slidably journaled thereon for movement into and out of engagement with a member of an engine to be started, a sleeve fixed on the shaft, a driven clutch member non-rotatably connected to the pinion, a driving clutch member splined on the sleeve, a shift collar slidably mounted on the sleeve, yielding means connecting the shift collar to the driving clutch, and means responsive to rotation of the power shaft above a predetermined speed for moving the pinion to idle position.

3. Engine starter gearing including a power shaft, a pinion slidably journaled thereon for movement into and out of engagement with a member of an engine to be started, a sleeve fixed on the shaft, a driven clutch member non-rotatably connected to the pinion, a driving clutch member splined on the sleeve, a shift collar slidably mounted on the sleeve, means connecting the collar to the driving clutch member adapted to yield compressively, and a centrifugal member rotatable with the connecting means for collapsing the connecting means to withdraw the pinion to idle position.

4. In engine starter gearing, a pinion, means including an overrunning clutch for rotating the pinion, manually operable means for moving the pinion into and out of engagement with a member of an engine to be started including a spring adapted to yield in case of tooth abutment between the pinion and engine member, and means for re-enforcing the spring after initial mesh of the pinion is secured.

5. In engine starter gearing, a pinion, means including an overrunning clutch for rotating the pinion, manually operable means for moving the pinion into and out of engagement with a member of an engine to be started including a toggle device arranged to yield in case of tooth abutment between the pinion and engine member, and means for bracing the toggle to stiffen it against endwise compression after the pinion is initially meshed with the engine member.

6. In engine starter gearing, a pinion, means including an overrunning clutch for rotating the pinion, manually operable means for moving the pinion into and out of engagement with a member of an engine to be started including a toggle device arranged to yield in case of tooth abutment between the pinion and engine member, supporting means for the central portion of the toggle, and means for flexing the toggle beyond its dead-center position and into engagement with said supporting means after initial mesh of the pinion with the engine member.

7. Engine starter gearing including a pinion movable axially into and out of mesh with a member of an engine to be started, means for rotating the pinion including an overrunning clutch having a slidably mounted driving member and a driven member connected to rotate the pinion, and manually operable means for transmitting longitudinal movement through the driving and driven clutch members to the pinion, said transmitting means including an elastic ele-

ment arranged to yield in case of tooth abutment between the pinion and engine member, and centrifugal means for collapsing the elastic element.

- 5 8. Engine starter gearing including a pinion movable axially into and out of mesh with a member of an engine to be started, means for rotating the pinion including an overrunning clutch having a slidably mounted driving member and a driven member connected to rotate the pinion, and manually operable means for transmitting longitudinal movement through the driving and driven clutch members to the pinion, said transmitting means including an elastic element arranged to yield in case of tooth abutment between the pinion and engine member, and means for stiffening the elastic element after the pinion is initially engaged with the engine member.

- 20 9. In engine starter gearing, a power shaft, a pinion slidably journaled thereon for axial movement into engagement with an engine gear, a sleeve fixed on the power shaft, and means for moving the pinion into mesh with the engine gear and for driving the pinion from the sleeve including a driven clutch member non-rotatably connected to the pinion, a driving clutch member splined on the sleeve, a manually operable shift collar, and a spring member connecting the shift collar and driving clutch member, said spring member being provided with a centrifugal weight element intermediate its length.

- 30 10. In engine starter gearing, a power shaft, a pinion slidably journaled thereon for axial movement into engagement with an engine gear, a sleeve fixed on the power shaft, and means for moving the pinion into mesh with the engine gear and for driving the pinion from the sleeve including a driven clutch member non-rotatably connected to the pinion, a driving clutch member splined on the sleeve, a manually operable shift collar, and a spring member connecting the shift collar and driving clutch member, said spring member being flat and being normally bowed outward but being permitted to bend in and obtain support for its mid-portion from the power shaft after initial mesh of the pinion with the engine gear.

11. In engine starter gearing, a power shaft, a pinion slidably journaled thereon for axial movement into engagement with an engine gear, a sleeve fixed on the power shaft, means for moving the pinion into mesh with the engine gear and for driving the pinion from the sleeve including a driven clutch member non-rotatably connected to the pinion, a driving clutch member splined on the sleeve, a manually operable shift collar, and a spring member connecting the shift collar and driving clutch member, said spring member being flat and so set as to have a natural deflection inward toward the axis of the drive, and means for bowing said spring outward away from said axis when the parts are in idle position, said means being arranged to allow the spring to bend inward and obtain support for its mid-portion from the power shaft after the parts are so moved as to obtain initial mesh of the pinion with the engine gear.

BURR W. JONES.
